UNITED STATES PATENT OFFICE.

TIMOTHY WEST, OF OAKLAND, CALIFORNIA.

PARCEL-POST CHART.

1,326,240.

Specification of Letters Patent. Patented Dec. 30, 1919.

Application filed June 24, 1914. Serial No. 846,985.

To all whom it may concern:

Be it known that I, TIMOTHY WEST, a citizen of the United States, residing at Oakland, in the county of Alameda and State 5 of California, have invented certain new and useful Improvements in Parcel-Post Charts, of which the following is a specification.

This invention relates to a chart to be used in connection with the determination 10 of parcel post rates, which has for its object the simplification of the method of determining the rates to any unit. My invention is intended to be used in connection with a parcel post guide, which gives the 15 unit in which each post-office of the United States is situated.

My chart comprises ninety eight unit plates corresponding in number to twice the number of degrees of longitude into 20 which the United States is divided, the plates representing respectively one unit in the half degrees of longitude of the United States. Each plate is divided by intersecting lines, of latitude and lines of longitude, 25 into squares corresponding to the parcel post units and by irregular zone lines into areas which correspond to the parcel post zones with relation to the particular unit which the plate represents. In the two abscissa 30 columns at the left of the plate are arranged the first two digits respectively of the parcel post unit numbers and in the ordinate column at the top of the sheet are arranged the last two digits respectively of the parcel 35 post unit numbers. Thus to find the zone in which any unit lies with relation to the unit which the plate represents, the first two digits of the unit number are located in the abscissa column at the left of the sheet and 40 the last two digits of the unit number are located in the ordinate column, and the intersection of the column extending to the right of the first digits of the unit number, and the column extending down from the 45 last digits of the unit number locates the unit and the zone lines between which said unit lies determines the zone in which the unit is located with relation to the unit which the plate represents.

50 A device of this character can be made more compact than the present parcel post maps with the circles drawn thereon, also more accurate in that no doubt exists as to the zone in which a unit lies, due to the 55 fact that a zone line passes through or close to the abutting corners of two adjacent units.

With these and other objects in view my invention consists in the novel construction and arrangement of elements as herein described and as more specifically pointed out 60 in the appended claim.

Reference should be had to the accompanying drawings forming a part of this specification wherein:

Figure 1 is a view of my improved chart 65 as arranged for unit 5573.

Fig. 2 is a fragmentary view of the edge of a chart arranged for unit 2973.

Fig. 3 is a view of a chart as arranged for unit 5523. 70

The unit plates of my chart are each divided into two sections 1 and 2. Said sections are divided by horizontal lines of longitude, one half of a degree of longitude apart, and by vertical lines of latitude, one 75 half of a degree of latitude apart, into squares equal to one-fourth the area of one degree longitude by one degree latitude, corresponding to the parcel post units of the United States. In the ordinate columns 3 80 and 4 at the top of each section 1 and 2 and at the head of the latitude columns are arranged the last two digits of the parcel post unit numbers from 01 to 49 and from 51 to 99 respectively. In two abscissa columns 5 and 6 at the left of the plates and at the head of the respective longitude columns are arranged the first two digits of the parcel post unit numbers. At the head of the columns 5 and 6 are indicated the 85 directions east and west which denote that the units having numbers beginning with the digits in said columns are east or west of the longitude divisional line which divides in half the degree of longitude in which the 90 local unit is located. Zone lines 7 are plotted along the unit lines on each plate which divide the plate into zones indicated 1 to 8 inclusive corresponding to the parcel post zones with relation to the local unit 100 which the plate represents.

To find the zone in which unit 3509 lies from unit 5573, by reference to plate 5573, Fig. 1, the first two digits 35 are located in column 5, and the last two digits 09 are 105 located in column 3, and the columns of longitude 35 and latitude 09 are followed respectively to the right and downwardly of the plate to their intersection in zone 6. This shows that unit 3509 is in the 6th zone 110 from unit 3573. As the first digit 35 is located in the east column 5, the unit 3509

lies east of the divisional line which divides the 55° of longitude in half, or east of the $54\frac{1}{2}^{\circ}$ of longitude according to the parcel post map. The directions E and W at the head of columns 5 and 6 determines what column the first two digits of the unit number are in and makes it easy to find said digits when it is known beforehand in which direction the unit to be found lies from the local unit. The division of the latitude digits in the columns 3 and 4 also simplifies the work in finding the last digits of a unit number.

It will thus be appreciated that with a chart of this character used in connection with a parcel post guide that the rates from local units are quickly and accurately determined, such determination being positive owing to the fact that the lines 7 are plotted in a zig zag manner rather than in a curve as are the circles drawn on the present maps.

What I claim and wish to cover by Letters Patent is:—

A parcel post chart comprising in combination, a plate divided into a pair of complementary sections each of which has rectangular coördinates, each of said sections having also irregular curves embodied thereon running along the coördinate line only,

the abscissæ of points between said curves being the first two digits of the numbers of unit areas in given zones as shown on a U. S. parcel post map, and the ordinates of points on each of said plates being the last two digits of the numbers of corresponding areas on said map, said irregular lines defining on the plate the areas of parcel post zones with references to a given center, each of said plates having its ordinates arranged in two columns, one of which is headed by the first two digits of the number of the local unit areas, the digits in the column headed by the local area decreasing from top to bottom and the digits in the other of said columns increasing from top to bottom, on one of said sections the two columns of ordinates having their tops on the same line and on the other of said sections the corresponding top of said second mentioned column beginning one line below the top of the column containing the local unit area.

In testimony whereof I affix my signature in presence of two witnesses.

TIMOTHY WEST.
